Primary Examiner — Keli L Hill

(57) CLAIM

The ornamental design for a combined grout brush set and holder, as shown and described.

DESCRIPTION

FIG. 1 is a back perspective view of the combined grout brush set and holder showing my new design in an unpacked position;

FIG. 2 is a front perspective view thereof;

FIG. 3 is a top view thereof;

FIG. 4 is a bottom view thereof;

FIG. 5 is a front view the combined grout brush set and holder in a packed position;

FIG. 6 is a back view thereof;

FIG. 7 is a left side view thereof;

FIG. 8 is a right side view thereof;

FIG. 9 is a top view thereof;

FIG. 10 is a bottom view thereof; and,

FIG. 11 is a perspective view thereof.

The broken lines shown in the figures are for the purpose of illustrating portions of the combined grout brush set and holder, which form no part of the claimed design.
